FOUNTAIN COMB

Carrie E. Holton, Daytona Beach, Fla.

Application January 2, 1942, Serial No. 425,456

2 Claims. (Cl. 132—13)

My invention relates to improvements in fountain combs for treating the hair and scalp.

The invention is designed with the particular object in view of providing a simply constructed comb for applying hot oil, or similar liquid, to the scalp and roots of the hair, easily and thoroughly, and which is leakproof, adapted for applying large or small amounts of oil, and inexpensive to manufacture.

To the accomplishment of the above, and to 10 subordinate objects presently appearing, a preferred embodiment of my invention has been illustrated in the accompanying drawing, set forth in detail in the succeeding description, and defined in the claims appended hereto.

In said drawing:

Figure 1 is a view in longitudinal section of a fountain comb embodying my improvement,

Figure 2 is a view in transverse section taken on the line 2—2 of Figure 1,

Figure 3 is a view in horizontal section taken on the line 3—3 of Figure 1, and

Figure 4 is a view in perspective of the valve operating plunger and cam.

Reference being had to the drawing by numerals, my improved fountain comb, in its preferred embodiment, comprises a substantially cylindrical, hollow back 1 having a front end 2 closed, with the exception of a screw hole 3 therein, a rear thicker end 4 having an axial bore 5 therethrough, and a row of tapered teeth 6 extending radially from one side thereof and which are axially bored, as at 7, for discharge of liquid therefrom and from the interior of the back 1.

A tubular liquid discharge member 8, of smaller diameter than the back 1, extends into said back 1 in the axis thereof by way of the bore 5 in which it tightly fits, said member having a front axially apertured end 9 by means of which and a screw 10 extending through the hole 3 and end 9 said member is secured to said back. The rear, open end of the discharge member 8 extends out of the back 1 and has threaded thereon the front end of a cylindrical, hollow handle 10 forming a liquid supply container and which is preferably of the same outside diameter as that of the back 1. The liquid discharge member 8 is provided, opposite the inner ends of the bores 7 of the teeth 6 with a single row of discharge ports 11 axially aligned with said bores 7.

A rubber gasket 12 is interposed between the back 1 and the handle 10 around the discharge member 8. A metal sleeve 13 surrounds the contiguous ends of the back 1 and the handle 55

10 and also the gasket 12 and which is preferably secured in any suitable manner to the back 1.

The handle 10 includes a rear end filler opening 14 closed by a screw plug 15. Fixed in the handle 10 is a spider 16 including a sleeve 17 in the axis of the handle 10. A rod-like valve stem 18 is slidably mounted in the sleeve 17 for endwise movement in opposite directions toward and from the rear end of the discharge member 8. A conical valve 19 is fixed on the front end of the stem 18 to seat in the rear end of the discharge member 8. A coil spring 20 on said stem 18 between the valve 19 and sleeve 17 yieldingly seats 15 said valve. A radial valve opening plunger 21 is slidably mounted in the handle 10 for movement inwardly thereof to open said valve 19, said plunger having a tapered cam 22 on its inner end, within said handle, coacting with a longitudinal 20 slot 23 in said valve stem 18 so that under movement of the plunger 21 inwardly of the handle 10, the valve stem 18 is cammed rearwardly to unseat the valve 19. A coil spring 24 is provided on the valve stem 21 intermediate the handle 10 25 and a push button 25 fixed on the outer end of said plunger 21, said spring yieldingly opposing inward movement of said plunger.

The operation of the invention will be readily understood. The handle 10 is filled with the 30 liquid, hot oil or the like, through the filler opening 14. The teeth 6 of the comb are rubbed against the scalp and oil admitted to the discharge member 10 by opening the valve 19, to be drained from the discharge member 8 by way of 35 the ports 11. By holding the comb with the teeth 6 upright, the liquid discharged through the ports 11 will be quickly fed to the teeth, and by tilting the comb laterally slowly fed to said teeth, as will be obvious. By means of the described 40 valve 19 a greater or less amount of liquid may be first admitted to the discharge member 8, as desired, before the teeth 6 are applied to the scalp. The comb may be formed of any suitable material.

45 The foregoing will, it is believed, suffice to impart a clear understanding of my invention without further explanation.

Manifestly, the invention, as described, is susceptible of modification without departing from 50 the inventive concept, and right is herein reserved to such modifications as fall within the scope of the subjoined claims.

What I claim is:

1. A fountain comb comprising a substantially cylindrical hollow back having front and rear end

webs the latter axially apertured and a longitudinal row of axially bored teeth on one side thereof opening into the interior of said back, a tubular liquid discharge member extending into said back by way of the rear web and spaced from the inner wall of said back, said member having a longitudinal row of ports therein opposite the rows of said teeth and being provided with a threaded rear end projecting out of said back, a hollow handle threaded onto said extended end of said member and forming a liquid supply container, a valve in said handle seating against the extended end of said member, and means to unseat said valve comprising a plunger slidably extended into said handle transversely thereof and provided with a push button.

2. A fountain comb comprising a substantially cylindrical hollow back having front and rear end webs the latter axially apertured and a

longitudinal row of axially bored teeth on one side thereof opening into the interior of said back, a tubular liquid discharge member extending into said back by way of the rear web and spaced from the inner wall of said back, said member having a longitudinal row of ports therein opposite the rows of said teeth and being provided with a threaded rear end projecting out of said back, a hollow handle threaded onto said extended end of said member and forming a liquid supply container, a valve in said handle seating against the extended end of said member, and means to unseat said valve comprising a plunger slidably extended into said handle transversely thereof and provided with a push button, and coacting camming devices on said plunger and valve.

CARRIE E. HOLTON.
